UNITED STATES PATENT OFFICE

2,177,338

CAR DOOR

Kenneth J. Tobin, Chicago, Ill., assignor to The Youngstown Steel Door Company, Cleveland, Ohio, a corporation of Ohio

Application January 28, 1938, Serial No. 187,357

10 Claims.

Cl. 16—99

This invention relates to car doors and more particularly to doors of the lift type for railway freight cars.

It is an object of this invention to provide doors for freight cars adapted to be frictionally supported when not being moved and to be elevated and supported upon either balls or rollers for movement between open and closed positions.

A further object is to provide lift doors of the character above set forth utilizing runways fixed against longitudinal movement wherein frictional support of the doors is insured when the lifting mechanism becomes inoperative.

A further object is to provide lift doors having swinging runways and capable of support upon balls or rollers for movement between open and closed positions.

A further object is to provide lift doors having swinging runways adapted when in horizontal position to support the doors during closing and opening travel upon the periphery of balls or rollers and to permit automatic lowering movement of the doors when swung to inclined position.

Other objects of the invention will become clear as the description thereof proceeds.

In the drawings forming part of this specification:

Figure 1 is a fragmentary elevation of a lift door embodying the invention, the door being illustrated in its lowered and closed position.

Figure 2 is a view similar to Figure 1, the door being illustrated in its open and elevated position.

Figure 3 is a vertical section taken on line 3—3 of Figure 1.

Figure 4 is a vertical section taken on line 4—4 of Figure 1.

Figure 5 is an end view of the door taken on line 5—5 of Figure 1.

Figure 6 is a vertical section taken on line 6—6 of Figure 2.

Figure 7 is a vertical section taken on line 7—7 of Figure 2, parts being omitted for the sake of clarity.

Figure 8 is a plan view of supporting rollers and their connecting carriage.

Referring to the drawings wherein a preferred embodiment of the invention is illustrated, there is shown a metallic door 10 whose construction embodies a metallic panel 11 preferably provided with spaced horizontal corrugations in the body thereof. At their ends the corrugations 12 merge into vertical corrugations 13 and 14 formed in the panel adjacent the vertical edges

thereof. At its lower margin the panel 11 is offset outwardly as indicated at 15 so as to provide a vertical depending flange 16 spaced outwardly from the main plane of the panel. A metallic backing plate 17 is secured to the main plane of the panel 11 as by means of rivets above the outwardly offset lower margin thereof and extends downwardly in substantially the main plane of the panel to cooperate with the offset margin to provide a housing or channel within which lifting mechanism hereinafter described is housed. The front vertical margin of the panel is reinforced by means of a substantially channel shaped member 18 and the rear vertical margin of the panel is reinforced by means of an angle 19 member.

Inasmuch as the door is of the lift type it is arranged to be frictionally supported upon a track 20 and for this purpose the front and rear vertical stiffeners are extended so that they may engage the track as clearly illustrated in Figures 1, 3 and 5 of the drawings. The track 20 is preferably in the form of an angle, the horizontal leg 21 of said track serving as the tread. The vertical leg 22 of the track extends downwardly from said tread for a purpose hereinafter set forth. By means of brackets 23 fastened to the horizontal leg 21 of the track as by rivets said track is rigidly secured to the side sill 24 of the car underframe.

Lifting mechanism is provided for elevating the door above the track and disposing it for support upon anti-frictional means in the form of rollers or balls for easy movement between closed and open positions. As hereinabove set forth this mechanism is housed and hence protected within the channel provided by the outwardly offset lower margin of the panel 11 and the backing plate 17. Such mechanism comprises a plurality of runways 25—25 swingably mounted upon the doors as more clearly shown in Figure 7 of the drawings. To this end a U-shaped member 26 disposed with its flanges 27—27 extending upwardly is utilized. A pin 28 passes through these flanges and the ends thereof find bearing in plates 29—29 secured as by welding to the flange 16 and the backing plate 17 respectively. The runways 25—25 are channel shaped in section with the flanges 30—30 extending downwardly. Each of the runways is secured to the member 26 preferably by welding together the web 31 of said member and the web 32 of the runway. The remote ends of the runways are closed by means of flanges 33—33.

Rollers 34—34 are shown for the purpose of

supporting the door during its travel upon the track 20. The instant invention is not limited to rollers but obviously may utilize balls for supporting the door. The rollers 34-34 are connected and maintained in properly spaced relationship by means of a carriage 35 which as more clearly illustrated in Figure 8 of the drawings is preferably formed of a metallic strap member 36 to each end of which is secured offset plate members 37-37. The rollers are disposed between these offset plate members and are mounted upon pins 38-38 received within openings formed in the plate members.

The lifting mechanism embodies additionally spaced bell cranks 39-39 pivoted intermediate their ends to the door. An additional bell crank 40 is provided and constitutes an extension of the actuating lever 41. The bell crank 40 is also pivoted to the door. The upper ends of each of the bell cranks are pivoted to a connecting bar 42 which is preferably flattened as indicated at 43, 44 and 45 for the purpose of said pivotal connections. The pivotal connection between the combined lever and bell crank and the connecting bar 42 is preferably obtained by means of a pin 46 formed integrally therewith. By reason of the connecting bar 42 it will be apparent that simultaneous rotation will be imparted to the bell cranks. At their remaining ends the bell cranks are provided with rollers 47. It will be observed from Figures 1 and 2 of the drawings that the lever 41 is extended upwardly through the housing so as to be available for operation of the door such extension being permitted by means of a slot 48 formed in the offset portion 15 of the panel.

In Figure 1 of the drawings the door is illustrated in its lowered and closed position. In this position the runways 25-25 are inclined longitudinally, the bell cranks are out of engagement with the runways and the door is in its lowered position so that frictional engagement between the vertical reinforcing members 18 and 19 and the track 20 is established thereby preventing longitudinal movement of the door upon the track. When it is desired to move the door from the extreme position shown in Figure 1 of the drawings to the extreme position illustrated in Figure 2 where the door is fully open, the actuating lever 41 is swung in counterclockwise direction thereby actuating the connecting bar 42 and simultaneously rotating the bell cranks 39 and 40 counter clockwise. The bell crank 40 and the bell crank 39 on the extreme right as viewed in Figure 1 of the drawings engage the runways 25-25 in the vicinity of the rollers 34-34 thereby exerting a lifting force upon the door through the pins pivotally maintaining said bell cranks. The door is thus elevated and during the elevation thereof the runways 25-25 will be swung from their inclined position to the horizontal position shown in Figure 2 of the drawings. When in this position the remaining bell cranks 39-39 will provide abutments for the runways. The door may then readily be moved to the position shown in Figure 2 of the drawings upon the supporting rollers 34-34. During this movement the door will be retained and guided upon the track by means of the guiding and retaining members 49-49 provided with hook portions 50-50 within which the depending vertical flange 22 of the track is received. When the door has reached the position shown in Figure 2 of the drawings release of the actuating lever 41 will cause the weight of the door to become effective to auto-

matically bring about lowering of the door and frictional engagement between the vertical reinforcing members 18 and 19 and the track 20. The runways 25-25 will swing to inclined position in order to permit such lowering movement of the door.

To move the door from its full open position to full closed position the operation set forth above is repeated. In this instance, however, the bell crank on the extreme left as viewed in Figure 2 of the drawings and the intermediate bell crank 39 will become effective to elevate the door. It will thus be apparent that alternate bell cranks cooperate functionally to elevate the door, their order depending upon whether the door is open or closed. The friction encountered in the elevation of the door is greatly reduced by the employment of the rollers 47 in the bell cranks.

It will be apparent from the foregoing that the door will automatically gravitate to lowered position whenever the actuating lever 41 is released and swinging of the runways 25-25 occurs regardless of the position of the door. At any position of the door intermediate its extreme position where release of the lever 41 and swinging of the runways 25-25 to inclined position occur, the door by virtue of its weight will move longitudinally along the track upon the rollers until the door reaches substantially one extreme position. The position finally arrived at will depend upon which side of the pivots of the runways the rollers are located when the runways begin to swing to inclined position. In the remote event these runways do not tend to assume their inclined position so as to permit the door to seat itself frictionally upon the track, jarring of the car will normally overcome this condition and the desired frictional engagement of the door with the track will be obtained.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. Lift mechanism for sliding car doors, said mechanism comprising a plurality of normally longitudinally inclined runways, a plurality of bell cranks operatively associated with said runways, said runways and bell cranks being swingably mounted on said door, a connecting bar for said bell cranks and a lever for actuating said bar.

2. Lift mechanism for a sliding car door adapted to be frictionally supported upon a track, said mechanism comprising normally longitudinally inclined runways swingably mounted upon said door, rolling means having peripheral engagement with said track and said runways and means carried by said door and cooperating with said runways for elevating said door for support upon said rolling means, said runways moving to horizontal position in response to the elevation of said door.

3. Lift mechanism for a sliding car door adapted to be frictionally supported upon a track, said mechanism comprising runways pivotally secured to said door, said runways being inclined longitudinally when said door is supported upon said track, rolling means having peripheral engagement with said runways and said track, bell cranks pivoted upon said door, a bar connecting said bell cranks for simultaneous operation and a lever for actuating said bar to swing said bell

cranks into engagement with said runways to elevate said door, said runways assuming a horizontal position in response to elevation of said door.

5. Lift mechanism for a sliding car door adapted to be frictionally supported upon a track, said mechanism comprising normally longitudinally inclined runways swingably mounted upon said door, rolling means having peripheral engagement with said track and said runways and means carried by said door and cooperating with said runways for elevating said door for support upon said rolling means, said runways being swung to horizontal position by said door during elevation thereof and means on said door forming abutments for said runways in said horizontal position.

10. Lift mechanism for a sliding car door adapted to be frictionally supported upon a track, said mechanism comprising runways pivotally secured to said door, said runways being inclined longitudinally when said door is supported upon said track, rolling means having peripheral engagement with said runways and said track, bell 15 cranks pivoted upon said door, a bar connecting said bell cranks for simultaneous operation and a lever for actuating said bar to swing said bell cranks into engagement with said runways to elevate said door, said runways being swung to horizontal position by elevaton of said door, certain of said bell cranks being effective to elevate said door while the remaining bell cranks serve as abutments for said runways in the horizontal position thereof.

15. Lift mechanism for a sliding car door adapted to be frictionally supported upon a track, said mechanism comprising runways pivoted intermediate their ends to said door, said runways being inclined longitudinally when said door is supported upon said track, rolling means engaging the elevated ends of said runways and said track, bell cranks pivoted upon said door, a bar connecting said bell cranks for simultaneous operation, and a lever for actuating said bar, said bell cranks bearing upon said elevated ends of said runways upon actuation of said lever to elevate said door.

20. Lift mechanism for a sliding car door adapted to be frictionally supported upon a track, said mechanism comprising runways pivoted intermediate their ends to said door, said runways being inclined longitudinally when said door is supported upon said track, rolling means en-

gaging the elevated ends of said runways and said track and operable means carried by said door adapted to bear upon the elevated ends of said runways for elevating said door.

25. Lift mechanism for a sliding car door adapted to be frictionally supported upon a track, said mechanism comprising runways pivoted intermediate their ends to said door, said runways being inclined longitudinally when said door is supported upon said track, rolling means engaging the elevated ends of said runways and said track, bell cranks pivoted upon said door, a bar connecting said bell cranks for simultaneous operation, and a lever for actuating said bar, said bell cranks bearing upon said elevated ends of said runways upon actuation of said lever to elevate said door, said door during elevation moving said runways to horizontal position.

30. Lift mechanism for a sliding car door adapted to be frictionally supported upon a track, said mechanism comprising runways pivoted intermediate their ends to said door, said runways being inclined longitudinally when said door is supported upon said track, rolling means engaging the elevated ends of said runways and said track, bell cranks pivoted upon said door, a bar connecting said bell cranks for simultaneous operation, a lever for actuating said bar, said bell cranks bearing upon said elevated ends of said runways upon actuation of said lever to elevate said door, said door during elevation moving said runways to horizontal position, and means carried by said door engaging the other ends of said runways when the latter are in horizontal position.

35. Lift mechanism for a sliding car door adapted to be frictionally supported upon a track, said mechanism comprising runways pivoted intermediate their ends to said door, said runways being inclined longitudinally when said door is supported upon said track, rolling means engaging the elevated ends of said runways and said track, bell cranks pivoted upon said door, a bar connecting said bell cranks for simultaneous operation and certain of said bell cranks bearing upon said elevated ends of said runways upon actuation of said lever to elevate said door, said door during elevation moving said runways to horizontal position, the remaining bell cranks engaging the other ends of said runways when the latter are disposed horizontally.

KENNETH J. TOBIN,
